C. C. ROBERTS

CLIP AND HANDLE FOR CIGAR BOXES

Filed Oct. 21, 1922

UNITED STATES PATENT OFFICE.

CHARLES C. ROBERTS, OF ANSONIA, CONNECTICUT.

CLIP AND HANDLE FOR CIGAR BOXES.

Application filed October 21, 1922. Serial No. 596,033.

To all whom it may concern:

Be it known that I, CHARLES C. ROBERTS, a citizen of the United States, residing at Ansonia, in the county of New Haven and

5 State of Connecticut, have invented certain new and useful Improvements in Clips and Handles for Cigar Boxes, of which the following is a specification.

This invention relates to clips for use 10 with cigar boxes for the purpose of maintaining the box in an inclined displaying position and at the same time supporting a device such as a price tag or ticket.

Among the several objects of my invention, 15 is that of providing a combined box support and price card holder which is formed of a single strip of material.

A further feature is that of the provision 20 of a clip which is maintained in operative position through its own resiliency.

Another feature is that of the provision 25 of a clip which will serve the purpose of a handle, through the medium of which the box may be lifted from the case to allow a customer to personally remove a cigar or cigars.

Other features reside in the various details of construction shown in the drawings and described in detail in the following 30 specification.

In the drawings,

Figure 1 is a top plan view of the blank from which the clip is formed;

Figure 2 is a side elevation of the clip;

35 Figure 3 is a side elevation of the clip and illustrating its application in use to a cigar box;

Figure 4 is a side elevation of the clip and illustrating an alternative use.

40 Figure 5 is a detailed view of a modified form of the invention.

The clip as more clearly shown in Figure 1, is formed from a single spring metal blank strip 4, which is formed preferably 45 during the stamping out operation, of a plurality of tongues 6, struck down from one plane face of the blank 4 and adjacent one end thereof, said tongues being preferably arranged in two or more parallel and longitudinal series.

50 The blank has further, and forward of the tongues 4, a pair of elongated tongues 8, extending longitudinally of the said blank, but struck down from the plane thereof in a direction opposite to that of

the tongues 4, said tongues 8 being adapted in practice, when the blank is formed into a clip, to provide a holding means for a price or similar card.

After the stamping operation, the blank 60 is bent to provide a straight arm 10, including the rearwardly directed tongues 4, which bite into the wall of the box as shown in Figure 3, said arm 10 being continued at one end and formed into an open 65 eye 14, the eye of which is indicated at 16. The body of the blank is then bent at 18 at substantially right angles, to form a return portion 20 which is itself continued in the form of an open loop or eye 22, the 70 end of which is directed toward the rear face of the arm 10, and terminates in a bevelled knife edge 24 adapted to bite into the lid 25 of the box upon its inner face. The card supporting tongues 8 are arranged at the top of the eye 14, and conform to the curvature thereof. As shown 75 in Figure 2, the biting tongues 4 and the knife edge 24 of the loop 22 are opposed, to the end that the natural resiliency of the 80 metal of the clip will tend to maintain the device securely against accidental displacement when applied to a cigar box. The loop or eye 22 provides a convenient means whereby the finger of a person may be 85 passed therethrough to disengage the clip when necessary, by lifting the knife edge from biting engagement with the wood of the lid.

The free end of the arm 10 is provided 90 with a triangular recess 28 having a beveled or knife edge, the terminal of said arm also being beveled as at 30. The purpose of this construction is to permit the device to be utilized as a box opener, the beveled edge 95 of the arm serving as an entering means between the lid and side of the box, while the recess 28 straddles the nail. As thus applied the lid may easily be pried open without damaging the box or its contents. 100

In Figure 4, I have shown an alternative manner in which the clip may be used as a supporting means for the box lid, the construction of the clip, however, being identical with that previously described. 105

In this construction and use as well as that shown in Figure 3, the loop 22 may be utilized as a handle whereby the box to which the clip is attached may be lifted 110 from the case so that the customer may per-

sonally remove the cigars therefrom, thereby avoiding contact of the dealer's fingers with the merchandise.

In the view shown in Figure 5, I have embodied the clip in still another form in which the bend 18 is omitted and the rearwardly turned portion is formed plain as at 40, this construction being particularly designed as a detachable self-holding handle.

From the foregoing description of the construction of my device, it will be seen that I have provided a simple inexpensive, and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention and illustrated its manner of use, what I claim as new and desire to protect by Letters Patent is:

1. A device of the character described,

comprising a resilient sheet metal clip having an arm provided with a series of biting tongues, a spring eye formed therewith having an open loop terminating in a knife edge directed toward said arm, and means formed on said arm for supporting a card.

2. A device of the character described, comprising a resilient sheet metal clip having an arm provided with a series of biting tongues, a spring eye formed on end thereof, an open loop formed as a continuation of said eye and terminating in a knife edge, said arm at its free end being provided with a nail straddling recess.

3. A self holding detachable clip handle for cigar boxes, comprising a straight member provided with biting tongues, a spring arm extending from the top of said member in the form of an open eye and thence continued to form an open loop whose extremity terminates in a knife edge that operates with said member to resiliently 45 50 55 clasp the box element.

In testimony whereof I affix my signature.

CHARLES C. ROBERTS.
